United States Patent

Des. 241,185
Patented Aug. 31, 1976

241,185

GARMENT

Jean V. Schlechter, 3016 Northway Drive,
Baltimore, Md. 21234

Filed Aug. 14, 1974, Ser. No. 497,480

Term of patent 3½ years

Int. Cl. D2—02

U.S. Cl. D2—82

FIG. 1

FIG. 3

FIG. 2

FIG. 1 is a front elevational view of a garment showing my new design;

FIG. 2 is a rear elevational view; and

FIG. 3 is a left side elevational view, the right side being a mirror image thereof.

The portion of the netting which would be seen through that shown has been omitted for convenience of illustration.

I claim:

The ornamental design for a garment, as shown and described.
